UNITED STATES PATENT OFFICE.

FELIX G. GARDNER, OF CELESTE, TEXAS.

PUMP.

SPECIFICATION forming part of Letters Patent No. 624,642, dated May 9, 1899.

Application filed March 26, 1898. Serial No. 675,274. (No model.)

To all whom it may concern:

Be it known that I, FELIX G. GARDNER, a citizen of the United States, residing at Celeste, in the county of Hunt and State of Texas, have 5 invented certain new and useful Improvements in Pumps; and I do hereby declare that the following is a full, clear, and exact description of the invention, which will enable others skilled in the art to which it appertains 10 to make and use the same.

This invention relates to pump mechanisms of that class which are adapted to operate to throw or force a stream of water to a desired height or a considerable distance and which 15 are adapted for use in fire-extinguishing and other general purposes, as desired.

The object of my invention is to provide a simple and improved pump mechanism or apparatus of this class which will possess advantages 20 in point of positive operation, inexpensiveness in construction, effectiveness, power, adaptability to various uses, convenience, and general efficiency.

In the drawings, Figure 1 is a top or plan 25 view of my improved pump mechanism. Fig. 2 is a plan view of the piston. Fig. 3 is a side or edge view of the apparatus. Fig. 4 is a detail transverse sectional view taken on the line $y-y$, Fig. 2. Fig 5 is a plan view of the 30 base-piece. Fig. 6 is a plan view of the middle piece. Fig. 7 is a transverse sectional view taken through the base-piece and its rim. Fig. 8 is a detail sectional view taken on the line $z-z$, Fig. 5. Fig. 9 is a transverse 35 sectional view taken through the middle piece. Fig. 10 is a detail transverse sectional view taken on the line $w-w$, Fig. 6. Fig. 11 is a transverse sectional view taken through the top piece. Fig. 12 is a detail transverse 40 sectional view taken on the line $x-x$, Fig. 1. Fig. 4^a is a detail perspective view of one of the valves.

Corresponding parts in all the figures are denoted by the same letters of reference.

45 Referring to the drawings, A designates the base-piece or bottom, which is provided with an annular rim a and with a segmental groove or channel a' in its top surface, having inclined or beveled ends a^2 a^2 , the purpose of 50 which groove or channel is to accommodate the valve when the whole is turned downwardly in the operation of the mechanism.

The inclined or beveled ends a^2 serve as guides for the valve in its rising movement.

B designates a revolving piston, which fits 55 within the rim of the bottom or base-piece and carries hinged valves C, arranged in a circular series. These valves are of right-angled construction, embodying a base arm or foot c , which is adapted to be received by 60 a corresponding recess b in the under side of the piston when the valve is up in an open position (illustrated in Fig. 4) and said foot is traveling upon the top surface of the base A. At right angles to the foot c the valve 65 comprises a head c' , which is adapted to rest upon a seat b' in the piston when the valve is closed. The valve is hinged, as at c^2 , at the vertex of the angle formed by its two arms or portions, as shown in Fig. 4. 70

D designates a middle piece which is mounted above the piston and is provided with a segmental slot d , which forms almost a complete circle and is adapted to accommodate the head c' of the valves. Communicating 75 with one end of the slot or passage d is an inlet e , through which the water is fed to the pump. At the opposite end of the slot d its diameter is contracted, as at d' d' , to provide inclined or beveled ways d^2 at the under side 80 of said contracted portion, which operates to carry the head c' of the valves downwardly and close them upon their seat b' . It will be understood that when the valves are thus closed their foot c is received by the groove 85 a' in the base A, and the head c' of the closed valve travels under the middle piece D until it reaches the initial end of the slot d at the inlet e , when the valve again rises in the slot d by means of the contact of its foot c with 90 the beveled ends a^2 of the groove a' , so that its head c' rises back of the water-supply and forces the same through the slot d .

F designates a cap-piece or cover which fits 95 over the piston and is provided with an outlet or opening f at the final end of the slot d , from which a suitable pipe or hose may extend, as desired.

The revolving piston is carried upon a shaft G, which extends transversely through the 100 pump device and has bearings in the base-piece or bottom A, as shown at g , in the middle piece D, as shown at g' , and in the cap-piece or top F, as shown at g^2 .

An operating-crank H may be attached to the outer end of the shaft G, or said shaft may be provided with any other suitable device by which it may be operated by hand or power, as desired.

The cap-piece F may be provided with segmental slots or openings f' f'', covered and closed by transparent plates i, of glass or other suitable material, through which the interior of the pump mechanism may be inspected.

The bottom or base-piece, piston, middle piece or member, and top or cap-piece are all preferably of flat circular or disk shape, having the relatively-arranged segmental slots or grooves, as above described, and assembled together in parallel superposed positions, as shown, whereby the whole forms a simple and compact pump device which will operate with great power and effectiveness.

The operation and advantages of my invention will be readily understood. The water enters at the inlet e into the segmental groove or passage d of the middle piece, and as the piston is turned or revolved by means of its shaft the hinged valves rise at the initial end of the slot d and force the water through the same and the outlet f at the terminal end of the slot, when the hinged valves close and pass under the middle piece D until they again reach the initial end of the slot d. The rotary operation of the piston and its hinged valves is adapted to force the water with great power, so that it will throw a stream for a considerable height or can be generally used for any desired purpose for which such mechanism is adapted.

Having thus described my invention, I claim and desire to secure by Letters Patent—

1. An improved pump of the class described, comprising a closed casing interiorly having a segmental groove or channel in its base portion and a relatively-arranged segmental passage above said groove or channel, water inlet and outlet connections at the respective ends of said passage, and a rotary piston ar-

ranged between said groove or channel and said passage and carrying angular valves operating upon a fulcrum and embodying divergently-projecting arms adapted to project respectively into said groove or channel and said passage when the valve turns upon its fulcrum, substantially as and for the purpose set forth.

2. An improved pump of the class described, comprising a closed casing embodying a base having a segmental groove or channel in its top surface, a middle piece having a relatively-arranged segmental slot or passage provided with water inlet and outlet connections at its respective ends, and a cap-piece or cover, in combination with a disk forming a rotary piston inclosed within said casing between the base and middle piece and carrying angular hinged valves embodying arms adapted to project at its opposite sides and in relation to said channel and said passage, substantially as and for the purpose set forth.

3. An improved pump of the class described, comprising a closed casing embodying in superposed relation a base having in its top surface a segmental groove or channel with guide-inclines at its ends, a middle piece having a relatively-arranged segmental slot or passage provided with water inlet and outlet connections at its respective ends and with a guide-incline at its terminal end extending with relation to said channel, and a cap-piece or cover, in combination with a rotary disk forming a piston and carried upon a shaft transversely mounted in said casing, said piston having mounted in it right-angular hinged valves the arms of which are adapted to project at opposite sides and operate in said channel and said passage, substantially as and for the purpose set forth.

In testimony whereof I affix my signature in presence of two witnesses.

F. G. GARDNER.
